UNITED STATES PATENT OFFICE.

LOUIS A. AMOUROUX, OF NEW YORK, N. Y.

MACHINE FOR OPENING OYSTERS.

SPECIFICATION forming part of Letters Patent No. 295,611, dated March 25, 1884.

Application filed August 31, 1883. (No model.)

To all whom it may concern:

Be it known that I, LOUIS A. AMOUROUX, of the city, county, and State of New York, have invented certain new and useful Improvements in Machines for Opening Oysters, of which the following is a specification.

This invention has reference to an improved machine for opening oysters in a quick and convenient manner; and the invention consists of a supporting-frame having standards for supporting a fulcrumed lever having a serrated jaw, against which latter the oyster is placed, and of an adjustable standard that is rigidly locked to the slotted base of the frame, and provided at its upper end with a twisted and pointed knife for severing the butt or hinged part of the shell.

In the accompanying drawings, Figure 1 represents a side elevation of my improved oyster-opener, partly in section. Fig. 2 is a plan; and Fig. 3, a vertical transverse section of the same on line $x x$, Fig. 2.

Similar letters of reference indicate corresponding parts.

25 In the drawings, A represents the base of my improved machine for opening oysters, which base is provided with two upright standards, A', that are cast integral therewith or otherwise rigidly attached thereto.

30 To the standards A' is fulcrumed a lever, B, having a serrated jaw, B'. A spiral spring, C, is attached to the jaw of the lever B by a staple, b, and to a hook, b', of the base A. The spring C serves to move the lever in an opposite direction to that exerted thereon by the hand in pressing the lever down. The base A is centrally recessed at a', and provided with transverse rods a'', which are secured to the base. A detachable standard, D, engages by 35 means of a downwardly-projecting hook, d, on one of the transverse rods a'', as shown in Fig. 1. In front of the hook d a metallic guard-heel, d', is arranged, which bears on the next adjoining rods a'', and secures thereby the rigid 40 connection of the standard D to the base A. The standard D is further provided at its upper part with a twisted and pointed knife, e, which projects forward, so as to enter the butt or hinged part of the shell. A face-plate, e', 45 of the standard D protects the face of the same, and serves to retain the knife e rigidly in position.

In operating my improved oyster-opening machine, the hook d of the detachable upright standard D is first placed over any one of the transverse rods a'', so as to be at any desirable distance from the serrated lever B, according to the size of the oysters to be opened. The oyster is then placed with its mouth against one of the teeth of the jaw, while the butt or hinged end of the shell is placed against the knife. The lever is then pressed down, the butt of the oyster forced against the knife, whereby the sinew that holds the two halves of the shell together is severed by the pointed end of the knife, and the sections of the shell then moved sidewise of their meeting edges by the twisted portion. The shell is then opened by a recessed knife, by which also the oyster is removed. In this manner oysters can be 70 quickly opened, and with great facility, even by inexperienced hands, and all the juice retained, as by the cutting of the hinged part of the shell no juice is lost.

The machine is adapted for domestic and 75 business purposes.

I am aware that oyster-openers in which a fixed serrated abutment and a reciprocating knife are employed have been used heretofore, and I do not claim the same.

Having thus described my invention, I claim as new and desire to secure by Letters Patent—

1. An oyster-opener consisting of a supporting-frame, a fulcrumed lever having a serrated jaw, an adjustable standard having a 85 fixed and twisting knife, and means whereby the standard is rigidly locked to the base of the frame, substantially as set forth.

2. The combination of a base, A, having fixed upright standards A', and a recess with 90 transverse rods a'', a fulcrumed lever, B B', an adjustable standard, D, having a fixed and twisted cutting-knife, e, and a bottom hook, d, and heel, whereby the standard D may be rigidly locked to the base at varying distances 95 from the jaw, substantially as set forth.

In testimony that I claim the foregoing as my invention I have signed my name in presence of two subscribing witnesses.

LOUIS A. AMOUROUX.
